ROOF FLASHING AND JACKET

Filed Nov. 3, 1928

*Inventor
Francis J. Moore
By his Attorneys
Merchant & Kilroe*

UNITED STATES PATENT OFFICE

FRANCIS J. MOORE, OF MINNEAPOLIS, MINNESOTA

ROOF FLASHING AND JACKET

Application filed November 3, 1928. Serial No. 316,970.

My present invention relates to a combined roof flashing and jacket for a vent pipe or the like and is in the nature of an improvement on or a refinement of the invention disclosed 5 and broadly claimed in my United States Letters Patent 1,279,572 issued September 24, 1918.

This roof jacket is circumferentially spaced from the vent pipe, to which it is applied, to 10 leave an air space or chamber between said jacket and pipe. Said chamber has a closed top and an open lower end, the latter of which affords communication with the interior of the building through the roof structure for 15 the passage of air therethrough to keep the air in the chamber at substantially the same temperature as that in the building to prevent formation of frost in the vent pipe by keeping the cold air outside of the building from 20 coming into contact with said pipe.

The formation of frost in a vent pipe is, of course, detrimental to the efficiency of said pipe for the reason that a cold vent pipe produces a poor draft and the conducting capacity thereof is often impaired by the building 25 up of frost within said pipe.

In installing this roof jacket, the purpose for which said jacket is intended, is often destroyed by placing the roof structure against 30 the vent pipe or in cutting a hole therethrough just large enough for the vent pipe and thereby closing the interior of the jacket to the interior of the building so that the jacket simply forms a dead air space.

35 The object of my present invention is to provide the roof flashing and jacket with a spacer to prevent the instillation thereof without leaving or forming an opening in the roof structure that is spaced from the vent pipe to form a passageway between the interior of the building and jacket.

To the above end, generally stated, the invention consists of the novel devices and combinations of devices hereinafter described and 45 defined in the claim.

The invention is illustrated in the single figure of the accompanying drawing wherein the view is partly in side elevation and partly in vertical section showing a roof structure and vent pipe extending therethrough and to

which structure and vent pipe is applied a flashing and jacket having the invention embodied therein.

The pitched roof structure, as illustrated in the drawing, includes a rafter 1, roof boards 2 and shingles 3. A vent pipe 4 is extended from the interior of the building upward through a hole 5 in the roof structure. Surrounding the vent pipe 5 above the roof structure is a flashing 6 which extends under the shingles 3 and is nailed to the roof boards 2. Applied to the flashing 6 is a jacket for the vent pipe 4 above the roof structure. This jacket comprises telescopically connected upper and lower sections 7 and 8, respectively, 60 the latter of which at its lower end is rigidly secured to said flashing by solder or otherwise. This flashing and jacket are of the type shown in the above identified patent and said flashing is readily adjustable to roofs of different pitch as fully described in said patent. By forming the jacket in two telescopically connected sections, said jacket may be readily longitudinally adjusted to vent pipes that project different distances above a roof. 65

A cap 9, of the type disclosed and claimed in my United States Letters Patent 1,647,414 issued November 1, 1927 and entitled "Roof jacket", is applied to the top of the vent pipe 4 and upper end of the upper jacket section 7. 70 It will be noted that the jacket is concentric with the vent pipe 4 and is spaced therefrom to leave an air chamber 10 between said jacket and vent pipe 4 and which chamber completely surrounds said pipe, is open at its 75 lower end and extends through the flashing 6.

A spacer 11 is provided to prevent the roof boards 2 from being closely positioned to the vent pipe 4 and thereby close the open lower end of the jacket and cuts off the warm air from the building to the chamber 10. This spacer 11, as shown, is in the form of a sleeve which forms a depending extension of the jacket and also the air chamber 10. The upper end of the spacer 11 is telescoped into the lower jacket section 8 and rigidly secured in respect thereto by solder or otherwise. The length of the spacer 11 is such as to extend below the flashing 6 and through the hole 5 in the roof boards 2. 95

By providing the flashing and jacket with the spacer 11 it is impossible to place the roof boards 2 close enough to the vent pipe 4 to close the open lower end of the chamber 10.

When installing the flashing and jacket after the roof boards 2 are in place, it is necessary to cut the hole 5 of such size as to permit the insertion of the spacer 11 therethrough.

The use of this spacer in connection with the roof flashing and jacket affords positive means to prevent the air chamber 10 from being closed by the roof structure. The spacer 11 is of substantially the same diameter as the jacket and hence maintains an air space therethrough of the same size in cross section as the chamber 10 and the distance to which the spacer 11 extends below the flashing 6 depends on the thickness of the roof structure to which said flashing is applied. Or in other words, the spacer must be of such length as to prevent the roof boards or other covering from closing the passageway from the building to the air chamber 10.

What I claim is:

The combination with a flashing having a raised intermediate portion, of a vent pipe jacket, the lower end of which is supported on said intermediate portion of the flashing and rigidly secured thereto, and a spacing sleeve telescoped into the jacket, extending through the raised intermediate portion of the flashing and below said flashing.

In testimony whereof I affix my signature.

FRANCIS J. MOORE.
